UNITED STATES PATENT OFFICE.

SPENCER G. NEAL, OF NEW YORK, N. Y., ASSIGNOR, BY MESNE ASSIGNMENTS, TO
AUTOMATIC STRAIGHT AIR BRAKE COMPANY, OF WILMINGTON, DELAWARE,
A CORPORATION OF DELAWARE.

CHANGE-OVER VALVE FOR AIR-BRAKE APPARATUS.

1,314,976.

Specification of Letters Patent.

Patented Sept. 2, 1919.

Application filed November 18, 1916, Serial No. 131,993. Renewed June 7, 1919. Serial No. 302,629.

To all whom it may concern:

Be it known that I, SPENCER G. NEAL, a citizen of the United States, and resident of the borough of Manhattan, city, county, and State of New York, have invented certain new and useful Improvements in Change-Over Valves for Air-Brake Apparatus, of which the following is a specification.

10 This invention relates to improvements in that type of valve for air brake apparatus shown and described in Patents No. 1,183,103, dated May 16, 1916, and No. 1,157,954, dated October 26, 1915. The air 15 retaining valve shown and described in said patents places the train pipe reservoir in communication with the train pipe during all service applications of the brakes, and means are provided whereby when the brake 20 cylinder pressure is equal to or above train pipe pressure, or when, after an equalization of train pipe and brake cylinder pressures, the brake cylinder pressure leaks down below the train pipe pressure and 25 augmenting reservoir pressure, the augmenting reservoir will be sealed against communication with the train pipe, and placed in communication with the brake cylinder so that the said reservoir capacity will be 30 added to the brake cylinder capacity and disconnected from the train pipe.

In the present invention the augmenting or train pipe reservoir is in communication with the train pipe during all service applications of the brakes, but upon an emergency application of the brakes the train pipe reservoir is disconnected from the train pipe and connected to the emergency 35 brake cylinder chamber 41 of the triple 40 valve, so that the train pipe reservoir capacity is added to the emergency reservoir capacity for emergency applications of the brakes.

One of the main objects of the invention 45 is to provide a valve which will be operated by the train pipe reservoir pressure to seal the train pipe reservoir from the train pipe upon a reduction of the train pipe pressure sufficient to secure an emergency application 50 of the brakes. It is desirable, upon a reduction of train pipe pressure, to secure an emergency application of the brakes, to reduce the train pipe capacity by sealing the train pipe reservoirs or disconnecting them

from the train pipe. By sealing the train 55 pipe reservoirs the volume of air contained therein is at once removed from the train pipe volume, thereby rendering it a simple matter to secure the proper reduction of train pipe air throughout the length of the 60 train.

Another object of the invention is to provide a valve operated by train pipe reservoir pressure which, upon a reduction of train pipe pressure sufficient to secure an 65 emergency application of the brakes, will place the train pipe reservoir in communication with the triple valve emergency brake cylinder chamber, so that the air from the train pipe reservoir may flow through the 70 triple valve chamber to the brake cylinder for an emergency application of the brakes.

In the triple valve shown and described in Patent No. 1,183,103, the triple valve with emergency brake cylinder chamber 41 is 75 illustrated and fully described, and it is thought that a diagrammatic representation of the triple valve will be sufficient for the purpose of illustrating the invention described herein.

In the drawing, Figure 1 is a diagrammatic view of a braking unit, showing the change-over valve connected thereto; and Fig. 2 a vertical central sectional view of the change-over valve.

Referring to the various parts by reference characters, A designates a triple valve which is to be constructed substantially in accordance with the triple valve shown in Patent No. 1,183,103; B an emergency reservoir; C a brake cylinder; D a train pipe reservoir and E a change-over valve.

The train pipe or augmenting reservoir D is connected to the train pipe through the controlling change-over valve E for all service applications of the brakes, precisely as shown and described in Patent No. 1,157,954. This valve consists of an outer main casing 1 forming a large train pipe chamber 2, said chamber being connected to the train pipe 3 through pipe 4. The upper wall of the chamber 2 is formed by a flexible diaphragm or movable abutment 5, which is clamped in position by the upper part 6 of the casing, said part forming an upper controlling chamber 7 above the diaphragm. The train pipe reservoir D is connected to the lower end of the change-over valve by

means of a pipe 8, said pipe opening into a chamber 9 formed by a cap 10 screwed on the lower end of the main casing 1.

Extending upwardly through the bottom 5 of the valve casing 1 and into the chamber 2, is an open-ended tubular post 11 having a valve 12 formed at its upper end. Sliding on this post is a sleeve 13 carried by the diaphragm 5 and adapted to be seated on 10 and unseated from the valve 12 by the variations in pressure in chambers 2 and 7. Through the center of the diaphragm is a passage 14 which places the chamber 2 in free communication with chamber 7. 15 Around the lower margin of the aperture 14 is formed a valve seat 15 which is adapted to receive and coöperate with the valve 12 of the tubular post 11. The sleeve 13 is enlarged at its upper end to form the small 20 chamber 16, and said chamber is in communication with the train pipe chamber 2 through the aperture 17, so that when the valve seat 15 is raised above the valve 12 on the upper end of the tubular post 11, chamber 2 will be in free communication 25 with the train pipe reservoir and with the chamber 7. Within the chamber 2 is arranged a coil spring 18, said spring bearing on the bottom wall of said chamber, and on 30 the under side of the diaphragm 5, and tending to separate the valve seat 15 and valve 12 and to maintain the train pipe chamber 2 in communication with the train pipe reservoir.

35 In the upper wall of the chamber 7 is formed an aperture 19 which is adapted to be closed by an upwardly seating valve 20 carried by the diaphragm 5, said valve being positively moved to and from its seat through 40 the movements of said diaphragm. The aperture 19 opens into a chamber 21 formed in a cap 22 to which pipe 23 is connected, said pipe leading from said chamber to the emergency brake cylinder chamber 41 of triple 45 valve A. As shown and described in Patent No. 1,183,103, the emergency brake cylinder chamber 41 is connected to the brake cylinder and is adapted to receive air from the emergency reservoir and to deliver it to the 50 brake cylinder for an emergency application of the brakes. As is also described in my said Patent No. 1,183,103, an emergency application of the brakes is secured by a sudden and pronounced reduction in train pipe 55 pressure.

In chamber 21 and seating downwardly on a valve seat formed at the upper end of the aperture 19, is a valve 20*. This valve is yieldingly held to its seat by means of a 60 light spring which is held in place by means of any suitable form of yoke or spider arm secured within the chamber 21. This valve prevents the passage of air from the chamber 21 through aperture 19 to the chamber 65 7, but is so lightly held to its seat that air

from chamber 7 may readily unseat it when the pressure in chamber 7 exceeds the pressure in chamber 21, plus the spring pressure on the valve 20*.

The operation of the apparatus may be 70 briefly described as follows:

Upon a sudden and prolonged reduction in train pipe pressure sufficient to secure the emergency application of the brakes, the pressure in chamber 2 will be sufficiently reduced to permit the air in chamber 7 to depress diaphragm 5 and bring the seat 15 of sleeve 13 down to valve 12, thereby closing communication between train pipe reservoir and the chamber 2. The reduction in 80 pressure in chamber 2 in an emergency application of the brakes, will take place more rapidly than air can flow from chamber 7 into chamber 2, so that the superior pressure in chamber 7 will depress diaphragm 5. As 85 the said diaphragm is depressed valve 20 is drawn downwardly from its seat, thereby placing chamber 7 in communication with pipe 23 and with the emergency brake cylinder chamber 41 of the triple valve. This 90 will permit air from the train pipe reservoir to flow through chamber 7 to the said emergency brake cylinder chamber, and from said chamber to the brake cylinder, as described in Patent No. 1,183,103, thereby adding the 95 train pipe reservoir volume to the emergency reservoir volume for an emergency application of the brakes. It is also manifest that by means of the air retaining valve shown in Fig. 2, the train pipe reservoir will be disconnected from the train pipe so that the air from said reservoir cannot flow into the train pipe upon an emergency application of the brakes. During all service applications of the brakes, however, the reduction 100 of pressure in chamber 2 will be comparatively slow, thereby permitting an equalization of pressures in chambers 7 and 2 and preventing the seating of the valve seat 15 upon valve 12. The spring 18 maintains the 105 diaphragm 5 in its upper position until there is a material preponderance of pressure in chamber 7. The excessive pressure in chamber 7 must be sufficient to overcome spring 18, and this preponderance of pressure will 110 only occur when the pressure in chamber 2 is reduced suddenly sufficient to secure the 115 emergency operation of the triple valve.

Should the pressure, at the time of an emergency application of the brakes, be 120 greater in chamber 41 of the triple valve and in chamber 21 of the change-over valve, than in the train pipe reservoir, the downwardly seating valve 20* will be held to its seat by the superior pressure in chamber 21. This will prevent emergency reservoir air passing back from chamber 21 to the train pipe reservoir.

By adding the train pipe reservoir volume to the emergency reservoir volume for emer- 130

gency applications of the brakes, the brakes will be maintained applied for a longer period than would be possible with the emergency reservoir volume alone, where brake cylinder leaks occur. It is manifest that the greater the air volume the longer period of time will be required to reduce the pressure through leakage.

What I claim is:

- 10 1. A change-over valve for an air brake apparatus comprising a casing, a diaphragm within said casing and dividing it into a train pipe chamber and a controlling chamber, a valve carried by said diaphragm and controlling communication between the controlling chamber and the train pipe and between the train pipe chamber and a train pipe reservoir, the controlling chamber being formed with an outlet, a valve carried by the diaphragm and opening said outlet when communication between the train pipe chamber and the controlling chamber is closed, and a valve to prevent air passing back through said outlet into the controlling chamber.
- 15 2. A change-over valve for an air brake apparatus comprising a casing, a diaphragm within said casing and dividing it into a train pipe chamber and a controlling chamber, a valve carried by said diaphragm and controlling communication between the controlling chamber and the train pipe and between the train pipe chamber and a train pipe reservoir, the controlling chamber being formed with an outlet, and a valve carried by the diaphragm and opening said outlet when communication between the train pipe chamber and the controlling chamber is closed.
- 20 3. A change-over valve for an air brake apparatus comprising a casing, a diaphragm within said casing and dividing it into a train pipe chamber and a controlling chamber, a valve carried by said diaphragm and controlling communication between the controlling chamber and the train pipe and between the train pipe chamber and a train pipe reservoir, the controlling chamber being formed with an outlet, a valve carried by the diaphragm and opening said outlet when communication between the train pipe chamber and the controlling chamber is closed.
- 25 4. A change-over valve for an air brake apparatus comprising a casing, a diaphragm within said casing and dividing it into a train pipe chamber and a controlling chamber, means adapted to connect the train pipe chamber to a train pipe, means to connect the
- controlling chamber with the train pipe chamber, means to connect the train pipe chamber with a train pipe reservoir, a valve operatively connected to the diaphragm and controlling communication between the train pipe chamber and the train pipe reservoir connection, and between the train pipe and the controlling chamber, means whereby train pipe reservoir air will at all times be supplied to the controlling chamber, the controlling chamber being formed with an outlet, and a valve carried by the diaphragm and controlling said outlet whereby upon a sudden reduction of pressure in the train pipe chamber, communication between the train pipe chamber and the controlling chamber will be closed and the outlet from the controlling chamber will be opened.
5. A change-over valve for use in that type of air brake apparatus in which the triple valve is operated by slow reductions of train pipe pressure to admit train pipe air to the brake cylinder for a service application of the brakes and in which a train pipe chamber is connected to the train pipe to augment the train pipe volume for service braking purposes, and wherein the triple valve is provided with means operating upon a sudden reduction of train pipe pressure to connect an emergency reservoir to the brake cylinder for an emergency application of the brakes, and comprising a casing, a diaphragm within said casing and dividing it into a train pipe chamber and a controlling chamber, means coöperating with said diaphragm and actuated thereby upon a sudden reduction of pressure in the train pipe chamber to close communication between the train pipe chamber and the controlling chamber and the train pipe reservoir, the controlling chamber being always in open communication with the train pipe reservoir, and means positively operated by the diaphragm to open communication between the controlling chamber and the triple valve to seal the train pipe reservoir from the train pipe and place it in communication with the triple valve in an emergency application of the brakes.
6. A change-over valve for air brake apparatus of the type defined in claim 5 and including means positively operated upon a sudden reduction in train pipe pressure to seal the train pipe reservoir from the train pipe and place it in communication with the triple valve, whereby the train pipe volume will be reduced and the train pipe reservoir air will be delivered to the triple valve during an emergency application of the brakes.

In testimony whereof I hereunto affix my signature.

SPENCER G. NEAL.
